RETRACTING SLIDE FOR FIREARMS

Arthur H. Jobert, New Britain, Conn.

Application May 20, 1944, Serial No. 536,588

16 Claims. (Cl. 89—191)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to automatic firearms such as rifles and carbines and more particularly to the slide for operating the bolt mechanisms (not shown) of such firearms. Specifically the invention relates to that type of operating slide disclosed in U. S. Letters Patent 2,308,283, issued January 12, 1943, and which is provided with short guide lugs on each side, which engage in long slideways or keyways on each side of the barrel thus permitting relative reciprocation. For the purpose of assembling and disassembling the slide from the barrel, a notch, which of necessity must be slightly wider than its coacting lug to permit the latter to drop through the slot, is provided in one of the keyways. This notch or cutway is provided in the left-hand keyway (looking towards the muzzle of the rifle). The slide is removed from the barrel by moving it to a position in which the left guide or lug can be engaged in the left keyway notch to permit it to drop therethrough, and then turning the slide slightly in a counterclockwise sense (still looking towards the muzzle of the rifle) until both the left and the right guide lugs are free from their respective barrel keyways. Several objections result from the fact that the left guide lug is slightly shorter than the assembling notch in the keyway to permit it to drop therethrough as it is obvious that the guide lug must jump across the notch in operation. The left guideway is also slightly beveled or chamfered where it joints the notch which has a tendency to "introduce" the lug into the notch, so to speak. Since most of the weight of the slide is carried by the left-hand guide lug, it has a tendency to drop into the notch which results in burring or peening of both ends of the lug and also the sides of the notch. This objectionable feature sets up a flutter or vibration in the slide which causes frequent breakage of the slide at various points. On manual manipulation of the slide, the guide lug frequently drops into the assembling notch and results in a definite stoppage of manual function.

It is accordingly an object of this invention to provide an operating slide which has a lug capable of completely bridging the notch on existing weapons while at the same time permitting the complete elimination of the notch in new weapons.

A further object is to provide an operating slide which is easier to remove from the barrel assembly while at the same time providing an oper-

2

ating slide which is completely interchangeable with the operating slides of existing weapons.

A further object is to provide an operating slide assembly, the several parts of which can readily be replaced without the use of any tools whatsoever.

A further object is to provide an operating slide assembly whereby the several parts are completely interlocked against disassembly so that there are no loose parts when the slide assembly is dismounted from the barrel assembly, while at the same time providing an operating slide assembly, the several parts of which can be readily disassembled from the slide proper by simple manual manipulation.

Other objects will be in part obvious and in part pointed out more in detail hereinafter.

Fig. 1 is a left side elevation of a portion of an existing carbine having the aforementioned left-hand dismounting notch;

Fig. 2 is an enlarged elevation of a portion of my improved operating slide;

Fig. 3 is a cross section on the line 3—3 of Fig. 2 and including the gun barrel, in locked condition;

Fig. 4 is a cross section similar to Fig. 3 but with the slide in unlocked condition;

Fig. 5 is a fragmentary bottom view of the improved slide;

Fig. 6 is a horizontal section on the line 6—6 of Fig. 3;

Fig. 7 is an isometric view of the locking mechanism of the improved slide, in locked condition; Fig. 7a is an isometric view of the same parts in unlocked condition; and Fig. 7b is an isometric view of those parts in disassembling condition;

Fig. 8 is a cross section in a plane corresponding to that of Fig. 3 of a modified form of operating slide;

Fig. 9 is a similar view of a second modified form of slide; and

Fig. 10 is a side view of the embodiment shown in Fig. 9;

Fig. 11 is a view taken on line 11—11 of Fig. 8. The present form of operating slide arrangement, briefly described above in the statement of invention, is shown in Fig. 1 wherein the operating slide is designated generally as 10. Operating slide 10 has a box-like channel portion 11 open at its top so as to provide clearance for the lower portion of the gun barrel 9. Extending rightwardly (in Fig. 1) from channel portion 11 towards the breech end of the gun is extension bar 13, near the right end of which is the cam ledge 14; at the right end of extension bar 13 is the

finger piece 15 extending laterally from the side of the gun (and hence largely hidden from view in Fig. 1). Left-hand keyway 8 is provided with the usual notch or cut-out 6 somewhat larger than the left-hand slide lug dotted at 18.

One form of improved operating slide of this invention is shown in Figs. 2 to 7b. The improved slide has a box-like channel portion 21, Figs. 2 and 5, with a left wall 25 and a right wall 24, open at the top; rod 23 extends breechwardly from the right wall 24. At the breech end of channel portion 21 left and right walls 25 and 24 are connected by end wall 22. As best seen in Figs. 3-4 and 6, the slide lug 27 projects inwardly from right wall 24 and is slidably received in the right keyway 7 of the gun barrel 9. The left slide lug 38, on the other hand, does not project from the left wall, but from an insert member 30 extending from top to bottom of the slide, which is mounted in a suitable cut-out provided in the left wall 25, see Fig. 2, of channel portion 21. Insert member 30, the lug 38 of which is slidably received in the left keyway 8 of the barrel, is mounted by means of a stud 36 fixed thereon and projecting therefrom, slidably received in a cylindrical bore 28 provided in the end wall 22 of channel portion 21.

In addition to the said horizontal bore 26, end wall 22 is also provided with a vertical cylindrical bore 28 in which is rotatively received a vertical pin 40. Vertical pin 40 cooperates with horizontal stud 36 of insert member 30 to provide for three conditions of the insert member relative to the slide or rather to channel portion 21 thereof, viz., (a) locked condition, in which insert member 30 is held in end wall 22 with its guide lug 38 received in barrel keyway 8, as shown in Figure 3, (b) unlocked condition, in which insert member 30 is held in end wall 22 with its guide lug 38 clear of barrel keyway 8, Fig. 4 (see Figure 7a), so that the operating slide may be removed from the barrel, and (c) disassembling condition (see Figure 7b), enabling the insert member to be separated from the retractor slide. Horizontal stud 36 is cut by a vertical groove or scallop 31, the upper half of which is of semicircular shape. The radius of the upper half of vertical scallop 31 is somewhat larger than the radius of vertical pin 40 so that the top portion of the pin (see Fig. 7) may be rotatively received therein. The position of vertical scallop 31 relative to insert member 30 and to the vertical pin 40 is such, see Fig. 3, that when the pin is held in the scallop, as it is in Figures 3 and 7, the vertical pin will block withdrawal movement of stud 36 and insert member 30 to the left. That is, the vertical pin 40 engages horizontal stud 36 to hold the insert member 30 in "locked condition" as defined above.

As best seen in Fig. 7, a semi-circular portion is removed from the left half of the top of vertical pin 40 leaving a semi-circular projection 41 constituting the right half and a depressed step 42 to the left thereof. It is the semi-circular projection 41 of the vertical pin which holds the insert member 30 in locked position, by abutting against, or fitting in, the right half (as viewed in Fig. 7) of vertical scallop 31 of horizontal stud 36. To the right of scallop 31, as viewed in Figs. 7, 7a and 7b, the horizontal stud 36 has a second scallop or groove 33 which differs from scallop 31 in that it does not extend clear through the horizontal stud 36 as does scallop 31. Scallop 33 occupies only the lower portion of stud 36, its upper extremity terminating in the horizontal plane which passes through the axis of stud 36. That is,

while the lower extremity of scallop 33 is open-ended (as are both extremities of scallop 31), the upper extremity of scallop 33 is defined by a horizontal, diametrical ledge 32 which overhangs scallop 33. The height of vertical pin 40 and the dimensions and position of its semi-circular projection 41 are such that the depressed step 42 of vertical pin 40 is somewhat below the level of the diametrical ledge 32 of horizontal stud 36. Hence when vertical pin 40 is turned on its longitudinal axis in cylindrical bore 28 (as will be subsequently referred to) its depressed step 42 will underlie the overhanging ledge 32 of horizontal stud 36, as is shown in Fig. 7a. In Fig. 7, vertical pin 40, more particularly, its upper projection 41, is reposed in scallop 31 of horizontal stud 36, with projection 41 abutting the right half of the scallop and thus blocking leftward movement of stud 36 and insert member 30; insert member 30 is thus held in its rightmost position, with its guide lug 38 retained in barrel keyway 8, this being the "locked condition," or locked position of the device, see also Fig. 3.

When it is desired to bring the parts to "unlocked condition" or position, from the one last described—so that the operating slide may be removed from the barrel—the vertical pin 40 is turned 90° in a clockwise sense (as viewed from above) from locked condition, Fig. 7, with the pin reposed in scallop 31, to unlocked condition, Fig. 7a. As the vertical pin is turned in this manner its semi-circular projection 41 is turned entirely clear of scallop 31 when the pin has completed its 90° turning. This is a consequence of the fact that the left edge of vertical pin 40 as viewed in Fig. 2 substantially intersects a vertical diametrical line through the horizontal stud 36. Therefore when the vertical pin is given a 90° turn as described, the vertical diametrical side 46 of projection 41 will be parallel to the horizontal stud 36 and slightly clear of the stud. By this 90° turning, the upper projection 41 of vertical pin 40 clears itself from the upper half of scallop 31 of the stud, i. e., that part of scallop 31 which lies above a horizontal plane through ledge 32.

It should be here pointed out that, while the upper half of scallop 31 is semi-circular with a radius somewhat greater than the radius of vertical pin 40, the lower half of scallop 31 is not in the shape of a semi-circle as is the upper half. The lower half of scallop 31 and the scallop 33 are not distinct grooves or scallops but form one continuous elongated recess. The left end of this recess is defined by a 90° curve which is the lower continuation of the upper half of scallop 31. The right end of the recess is also defined by a 90° curve having the same radius as that of the left end and scallop 31. Between these two curved ends, the recess has a straight portion which extends axially along a vertical diametrical plane. Because of this central straight portion of recess 31—33, no obstruction is offered to that portion of vertical pin 40 which is below depressed step 42. When pin 40 is turned 90° to the position shown in Fig. 7a, the stud 36 is enabled to move leftwardly relative to vertical pin 40, until pin 40 abuts the right curved end of the recess, i. e., the right wall of scallop 33. Horizontal stud 36 is impelled to move leftwardly by a compression spring 35 confined by the stud in a reduced coaxial counterbore at the inner end of the bore 26. This extent of leftward movement of stud 36 and insert member 30 is sufficient to withdraw guide lug 38 from

barrel keyway 8, Fig. 4. The parts 36 and 40 in the last named relation may be said to constitute a lost motion connection between the insert 30 and the slide.

For the purpose of providing a means by which vertical pin 40 may be turned, there is secured to its lower end a resilient strip 47. As clearly seen in Figs. 7, 7a and 7b and in the bottom plan view of Fig. 5, one edge of strip 47, designated 47b, is tangent to the pin 40, while the other edge 47a extends somewhat beyond so as to present a short ledge along that side. Also, the proximal end of strip 47 extends a short distance beyond pin 40 so as to present a short rear ledge or flange 49. The underside of wall 22 of the operating slide is provided with a lip 29 which cooperates with the tangent edge 47b, the extended edge 47a and the rear ledge 49 of the strip 47 in the following manner. When the vertical pin 40 is turned to locked condition, which angular position of the pin is shown in the solid line position of its strip 47 in the bottom plan view of Fig. 5, the extended edge 47a of strip 47—more particularly, the portion of extended edge 47a which borders pin 40—will overlie lip 29. Lip 29 therefore will prevent downward withdrawal of pin 40 in the locked condition of the parts. Leftward withdrawal of insert member 30 is prevented by the fitting of vertical pin 40 in scallop 31, as described above.

The lip 29 also prevents downward withdrawal of pin 40 when turned in unlocked condition. The unlocked angular position of pin 40 is shown in Fig. 5 by the dot-and-dash position of its strip 47 which is normal to the solid-line, locked position of strip 47. In this unlocked position of strip 47 (dot-and-dash) the rear ledge 49 of the strip overlies lip 29. Lip 29 therefore will prevent downward withdrawal of pin 40 in the unlocked condition of the parts. Leftward withdrawal of insert member 30 is prevented by the fitting of vertical pin 40 in scallop 33, as described above.

When it is desired to disassemble the parts, vertical pin 40 is given another 90° clockwise turn, so that it is now 180° from the locked position of Fig. 7. The disassembling position is shown in Fig. 7b, where it will be seen that the semi-circular projection 41 is now on the left of the pin. The horizontal stud 36 must first manually be moved rightwardly by pressure on insert member 30 in order that the projection 41 may clear in the scallop 31. In the disassembling position of pin 40, which is shown by the dotted line position of its strip 47 in Fig. 5 (aligned but opposed to its locked position shown in solid lines), the tangent edge 47b of the strip now faces the lip 29 but does not overlie it. Hence when the pin 40 and its strip 47 are turned to disassembling position, lip 29 will not prevent the downward withdrawal of pin 40. After the pin has been removed, the insert member 30 may be withdrawn leftwardly.

Strip 47 is made of spring metal the distal end of which is bent slightly upward so that it will snap into locked position behind a locking or retaining lug 20 for the purpose of securing it in locked condition. The underside of the retracting slide, more particularly the underside of end wall 22 is provided with a projecting lug 20, see Fig. 5, which is just to the right of strip 47 when in locked condition (solid lines in Fig. 5). That is, strip 47 is held firmly in locked condition by the abutment of its edge 47a against a stop edge 22e provided on the underside of

wall 22 of the slide and by the abutment of its other edge 47b against the lug 20. To turn the pin from its locked condition, the distal end of its strip 47 is sprung over the lug 20 and the strip and pin turned in a counterclockwise sense, as viewed in Fig. 5 (which is a bottom plan view).

The improved retracting slide of Figs. 2 to 7b does not require the provision of a notch in the keyway of the barrel. The improved retracting slide may be used on carbines which had been provided with the present type of retracting slide and whose left keyway 8, see Fig. 1, has a dismounting notch 6. In such cases the guide lug (left) 33 of the insert member 30 must be made sufficiently long to span the keyway notch 6, see Fig. 6, in order not to drop therethrough.

A modified form of operating slide is shown in Figs. 8 and 11, where insert member 58, whose guide lug 58 is withdrawable leftwardly from the barrel keyway, has a stud 56 which is slidably received in a cylindrical bore 59 provided in wall 22 of the slide. The distal end of stud 56 is provided with a notch 55 opening on its upper surface. Notch 55, which is less than a full circle but greater than a half-circle, is cut to a radius somewhat larger than the radius of the tenon 5 of the operating spring guide rod 54 of the prior gun. The wall 22 of the slide is bored and counterbored at 53, as in the prior gun, and functions as before to afford a seat for the rod 54 which is held thereto by the conventional drive spring 52 of the prior gun. The position of stud 56 and its notch 55 are so related to the spring guide rod 54, that end of the tenon 5 will engage the notch 55 to hold stud 56 and insert member 58 in locked condition, as shown in Figs 8 and 11.

Since it is necessary to remove the spring guide rod 54 and its associated recoil and drive spring 40 to dismount operating slide 10, it is obvious that insert member can be readily removed when the end tenon 5 of spring guide rod 54 is disengaged from notch 55 of stud 56.

Another modified form of operating slide is shown in Figures 9 and 10, where insert member 60 has a position and function corresponding to those of insert member 30 and is pivotally mounted to wall 22 on a pin 61 set through member 60 and projecting at front and rear on each side thereof. Pin 61 is journaled in a deep slot 67 cut in side wall 25 and parallel with the normal axis of the slide. This slot has parallel sides which are inclined upwardly and outwardly at an angle of slightly less than forty-five degrees to the horizontal. The insert 60 has a lower end portion 70 extended inwardly in the slot 71 which forms a continuation of the cutout 72 in which the insert is set. The end portion 70 has a top side 73 which is inclined downward and inward at an angle of less than 45 degrees to the horizontal but somewhat more steeply than the inclination of the sides of the slot 67 as shown. The top side of the slot 71 is at a more acute angle to the horizontal, so that a space is afforded thereunder for rocking of the end 70 on the pin 61. A spring pressed plunger 63 is slidably held in cylindrical bore 69 provided in wall 22. Bore 69 is substantially at a normal to angular slot 67. The outer end of pin 63 is pointed to be seated in a cavity or hole 62 provided in pivoted member 60. A compression spring 64 within bore 69 and between its bottom and pin 63 urges the pin outwardly to turn pivoted member 60 in a clockwise sense and thus to maintain the guide lug 68 in the left keyway of the barrel. The op-

erating slide is removed from the barrel by turning member 60 counter-clockwise to withdraw the lug 68. To facilitate the manual withdrawal of lug 68 upon turning member 60, the upper surface of lug 68 may be beveled as at 66.

This device also has a manner of operations by which the insert 60 may be disengaged from the slide simultaneously with the freeing of the slide for removal from the barrel. In the latter operation, the bevel at 66 and the inclination of the top face 73, permit the insert 60 to be pressed translatively toward the left and upward, and if necessary then a slight pivotal movement in which the insert 60 pivots at the lug 68, so that the whole insert rotates slightly around the lug 68, the actual axis of such rotation being shifted laterally outward as the lug moves out of the left keyway of the barrel, the slide being at the same time rotated slightly on a longitudinal axis of the gun at the right hand lug 27. The latter movement corresponds to the take-down movement of the slide in the prior gun when the left guide lug was aligned with the keyway notch of the conventional barrel. The loose fit of the left guide lug in the keyway as usually practiced heretofore also contributes to permitting the initial movement of the pin 61 in the slot 67. In the last described disassembly movement of the insert 60, the plunger 63 and its spring 65 co-act with the cavity 62 as a "bullet latch," opposing the movement, by the cam action of the nose of the plunger against the side of the cavity 62. The plunger is cammed upward as the side of the cavity wipes transversely on the plunger in the translative movement of the insert.

To disassemble member 60 from the slide it is merely necessary to insert the reduced end of spring guide 54 (not shown) or other pointed article into hole 62 to disengage its coacting plunger, and while the plunger is thus held, member 69 is moved to the left and upward parallel with slot 67. It will be seen from the foregoing that plunger 63 effectively holds member 60 assembled to the operating slide, while at the same time permitting partial rotation of member 60 about its fulcrum 61 to disengage lug 68 from its coacting keyway.

While I have described my invention as it relates to firearms, it is obvious that it is susceptible to various modifications and changes; that it can be applied to other mechanisms and devices without departing from the scope of the appended claims.

I claim:

1. In a firearm of the character described, in combination, a barrel provided with keyways along both sides thereof, a channel portion having parallel side walls receiving the barrel slidably therebetween and an end wall shortened in height to provide clearance for the said barrel, one of the side walls having a cut-out adjacent the said end wall, a movable insert member pivotally mounted in the said wall cut-out, a slide lug inwardly projecting from the said insert member and a slide lug inwardly projecting from the opposite side wall, the said lugs being slidably received in respective said keyways, and spring means for yieldably holding the said insert member in a position to maintain its said slide lug in the barrel keyway, the said insert member being manually displaceable to withdraw its slide lug from the barrel keyway.

2. An operating slide for firearms provided with a spring retainer rod and a barrel having keyways along both sides thereof, comprising, in

combination, a channel portion having parallel side walls and an end wall shortened in height to provide clearance for the said barrel, one of the side walls having a cut-out at the said end wall, an insert member positioned in the said wall cut-out, a slide lug inwardly projecting from the said insert member and a slide lug inwardly projecting from the opposite side wall slidably received in the barrel keyways, the said channel portion having a hole extending longitudinally into the said opposite side wall and transversely through the said end wall for receiving the said spring retainer rod, the said end wall having a cylindrical bore extending longitudinally thereof from the said wall cut-out and intersecting the said hole, a spindle projecting from the said insert member and received in the said bore, the distal end of the said spindle having a recess to receive the said spring retainer rod, and the said spindle recess being positioned to cause the said rod to hold the insert member with its slide lug locked in the barrel keyway.

3. In a firearm of the character described, a barrel, guideways on the barrel, a slide mounted for reciprocation along the barrel, said slide including lugs slidably engaged in respective guideways, at least one of said lugs being a movable lug engaged retractably in one guideway, an interlocking member normally in locking position in relation to said lug and constructed to hold the lug in engagement with said one guideway when at said position, and being movable to an unlocked position in relation to said lug, distally extending resilient means fixed on and movable with said interlocking member, said slide having a slot positioned to receive one end of said resilient means at locking and unlocked positions, said resilient means coengagable with said slot to hold the interlocking member against removal while in and between both said positions, a locking shoulder on the slide for engagement with the distal end of said resilient means when at said locking position, said resilient means being manually displaceable to clear the shoulder.

4. The structure of claim 3 in which said interlocking member has a third position at which it is movable from the slide and lug, said resilient member movable therewith to the third position and being constructed to clear said slot at the third position.

5. The structure of claim 3 in which said interlocking member has a third position movable from the lug and slide, said resilient member movable therewith to the third position and being constructed to clear the said slot at the third position, said lug and interlocking member constructed to lock the latter against separation when the lug is retracted, and resilient means to hold the lug at retracted position yieldable to manual replacement.

6. The structure of claim 3 in which said interlocking member is a rotatable member movable angularly to and from said positions and movable also to a third position for disassembly, said resilient member constructed to clear said slot at the third position, and said interlocking member being slidably longitudinally of its axis of rotation from the lug and slide at said third position, when the lug is in one position.

7. The structure of claim 3 in which said interlocking member is a rotatable member movable angularly to and from said positions and movable also to a third position for disassembly, said resilient member constructed to clear said slot at the third position, and said inter-

locking member being slidably longitudinally of its axis of rotation from the lug and slide at said third position when the lug is in one position, said lug being constructed to clear the interlocking member for withdrawal of the latter when the lug is in engaged position and to interlock with the interlocking member to prevent withdrawal of the member when the lug is at retracted position, and resilient means to urge the lug toward retracted position, yieldable to manual pressure.

8. In a firearm, the combination therein of a barrel having diametrically opposite guideways, an operating slide about said barrel and adapted to reciprocate relative to the same, a first lug integral with said slide and extending laterally inward thereof and slidably engaging one of said guideways, a second lug slidably engaging the other of said guideways, said slide having a cut-out portion, an insert movably mounted in said cut-out portion and carrying said second lug, a stud fixed to said insert normal thereto and laterally slidable in said slide, spring means in said slide biasing said stud transversely of said slide, said stud having a semi-circular recess and an elongated recess adjacent thereto, a cylindrical pin rotatably mounted in said slide normal to said stud and received within said elongated recess, said cylindrical pin adapted to be rotated sequentially from an initial position to a terminal position through an intermediate position, a semi-cylindrical projection on one end of said cylindrical pin and adapted to be rotated into said semi-circular recess when said cylindrical pin is rotated to either the initial or terminal positions whereby said stud is held against lateral movement relative to said slide, said projection being adapted to be rotated out of said semi-circular recess when said pin is rotated to the intermediate position whereby said stud is freed for lateral movement by said spring means, the end of said cylindrical pin riding in said elongated recess and adapted to abut an end wall of the same to limit movement of said stud by said spring means, a curved leaf spring secured to the end of said cylindrical pin opposite to said semi-cylindrical projection and extending at the same side of the axis of said cylindrical member, a slot extending transversely on said slide, said leaf spring having an offset portion adapted to extend into said slot when said cylindrical pin is in the initial or intermediate position whereby said cylindrical pin is held against axial displacement in said slide, and whereby rotation of said cylindrical pin to the terminal position will disengage said offset portion from said slot freeing said pin for removal from said slide by axial movement.

9. In a firearm, the combination therein of a barrel having diametrically opposite guideways, an operating slide about said barrel and adapted to reciprocate relative to the same, a first lug extending from said slide and slidably engaging one of said guideways, a second lug slidably engaging the other of said guideways, an insert carrying said second lug, a stud fixed to said insert normal thereto and slidably mounted in said slide, spring means in said slide biasing said stud transversely of said slide, said stud having a recess, a pin rotatably mounted in said slide, said pin adapted to be rotated sequentially from an initial position to a terminal position through an intermediate position, a projection on one end of said pin and adapted to be moved into said recess when said pin is rotated to either the initial or terminal positions whereby said stud is held against axial

movement relative to said slide, said pin being adapted to be moved out of said recess when said pin is rotated to the intermediate position whereby said stud is freed for axial movement by said spring means, a leaf spring secured to the end of said pin, a slot extending transversely on said slide, said leaf spring having an offset portion adapted to extend into said slot when said pin is in the initial or the intermediate position whereby said pin is held against axial displacement from said slide, and whereby rotation of said pin to the terminal position will disengage said offset portion from said slot freeing said pin for removal from said slide by axial movement.

15 10. In a firearm, the combination therein of a barrel having diametrically opposite guideways, an operating slide adapted to reciprocate relative to said barrel, a first lug extending from said slide into one of said guideways, a second lug engaging the other of said guideways, an insert attached to said second lug, a stud fixed to said insert and movable on said slide, spring means in said slide biasing said stud transversely of said slide, said stud having a recess, a pin means removably mounted in said slide and said recess whereby said stud is held against movement relative to said slide, said pin means being adapted to be moved out of said recess to free said stud for lateral movement by said spring means, and means on the end of said pin for releasably retaining said pin in said slide.

35 11. In a firearm, the combination therein of a barrel having diametrically opposite guideways, an operating slide, a pair of lugs thereon engaging said guideways, respectively, for supporting said slide for reciprocatory movement, one of said lugs being retractable from said respective guideway, movable means on said slide supporting said retractable lug for movement transversely of said respective guideway, locking means on said slide interengaging with said movable means for holding the same against movement relative to said slide whereby said retractable lug is retained in said respective guideway.

45 12. In a firearm, the combination therein of a barrel having diametrically opposite guideways, an operating slide adapted to reciprocate relative to said barrel, a first lug extending from said slide into one of said guideways, a second lug 50 engaging the other of said guideways, a support means carrying said second lug and movably mounted on said slide, and removable means in said slide releasably holding said support means against movement relative to said slide whereby said second lug is retractably held in said other of said guideways.

60 13. In a firearm of the character described, a barrel, guideways in said barrel, a slide mounted for reciprocation on said barrel and having a lug engaged in one of the guideways, a movable lug 65 retractably engaged in the other of said guideways to hold the slide releasably on said barrel, an interlocking member for normally holding said movable lug in engagement with said respective guideway, distally extending resilient means included with said interlocking member movable therewith from a locked position to a released position, said slide having a slot for receiving one end of said distally extending resilient means when at said locked position, and to clear the same when at said released position, and a locking shoulder on said slide for engagement with the distal end of said resilient means, said interlocking member and resilient means being removable from the remainder of said slide

when said movable lug is engaged with its coacting guideway to permit disengagement of said resilient means from its coacting locking shoulder and slot.

14. In a firearm of the character described, in combination, a barrel provided with keyways along both sides thereof, a channel portion having parallel side walls receiving the barrel slidably therebetween and an end wall shortened in height to provide clearance for the said barrel, one of the side walls having a cut-out adjacent the said end wall, a movable member positioned in the said wall cut-out, a slide lug inwardly projecting from the said insert member and a slide lug inwardly projecting from the opposite side wall, the said lugs being slidably received in said barrel keyways, the said end wall having a horizontal bore open at the said wall cut-out and a vertical bore open at the bottom, an inwardly projecting horizontal stud fixed on said insert member and slidably received in the said horizontal bore, a vertical pin rotatively received in the said vertical bore and manually turnable selectively to "locked," "unlocked" and "disassembling" positions, means preventing bottom withdrawal of the pin in its said "locked" and "unlocked" positions but permitting pin withdrawal in its said "disassembling" position, the said horizontal stud and the said vertical pin having coacting elements constructed and arranged in the said "locked" position of the pin, to prevent withdrawal of the insert member whereby its said slide lug is locked in the barrel keyway, and constructed and arranged in the said "unlocked" position of the pin, to permit a limited withdrawal of the insert member sufficient to withdraw its slide lug from the barrel keyway, the said withdrawal of the pin in its said "disassembling" position permitting the stud to be removed from its horizontal bore.

15. In a firearm of the character described, in combination, a barrel provided with keyways along both sides thereof, a channel portion having parallel side walls receiving the barrel slidably therebetween and an end wall shortened in height to provide clearance for the said barrel, one of the side walls having a cut-out adjacent the said end wall, a movable insert member positioned in the said wall cut-out, a slide lug inwardly projecting from the said insert member and a slide lug inwardly projecting from the opposite side wall, the said lugs being slidably

received in said barrel keyways, and means including a withdrawable element manually turnable selectively to "locked," "unlocked" and "disassembling" positions, said element having blocking relation to the insert member in the direction of withdrawal of the latter when the said element is in its said "locked" position whereby the lug of the insert member is locked in the barrel keyway, said means so constructed and arranged that with said element in its said "unlocked" position it constitutes a lost motion connection between the insert member and slide to permit limited positioning of the insert member sufficient to withdraw its slide lug clear of the barrel keyway, the said element having a free relation to the remainder of said means and removable therefrom when the said element is in its said "disassembling" position.

16. In a firearm, a barrel having longitudinally extending guideways, a slide provided with lugs in slidable engagement with the guideways for slidably connecting the slide to the barrel; said slide including a movable section containing one of said lugs and movable relatively to the slide for disengaging said section from the slide for demountably attaching the remainder of the slide to the barrel; said slide having a recessed portion, said movable section having a projection extending into said recessed portion and provided with a latch-receiving portion, and a latch member slidably mounted in the slide and normally engaging said latch-receiving portion for detachably retaining the movable section in a position in which the lug carried thereby is held in operative engagement with its guideways.

ARTHUR H. JOBERT.
